UNITED STATES PATENT OFFICE.

MAX KLEIN, OF NEW YORK, N. Y., ASSIGNOR TO SHAPIRO & ARONSON, INC., OF NEW YORK, N. Y., A CORPORATION OF NEW YORK.

DESIGN FOR A LIGHTING UNIT.

57,358.

Specification for Design.

Patented Mar. 15, 1921.

Application filed August 19, 1920. Serial No. 404,691. Term of patent 3½ years.

To all whom it may concern:

Be it known that I, MAX KLEIN, a citizen of the United States, residing at New York, in the county of New York and State of New York, have invented a new, original, and ornamental Design for a Lighting Unit, of which the following is a specification, reference being had to the accompanying drawing, forming part thereof.

The figure is a perspective view of a lighting unit embodying my new design.

I claim:

The ornamental design for a lighting unit as shown.

MAX KLEIN.
